UNITED STATES PATENT OFFICE.

ACHILLES H. VAN PAEMEL, OF CHICAGO, ILLINOIS.

CONCRETE BUILDING CONSTRUCTION.

1,171,282.

Specification of Letters Patent.

Patented Feb. 8, 1916.

Application filed May 6, 1915. Serial No. 26,232.

To all whom it may concern:

Be it known that I, ACHILLES H. VAN PAEMEL, a citizen of the United States, and a resident of the city of Chicago, county of Cook, and State of Illinois, have invented certain new and useful Improvements in Concrete Building Constructions, of which the following is a specification.

My invention relates to improvements in concrete building construction, and more especially to an improved construction for securing laths thereto.

The invention consists in the combinations and arrangements of parts hereinafter described and claimed.

The invention will be best understood by reference to the accompanying drawing forming a part of this specification, and in which,

20 Figure 1 is a top plan view of a portion of a wall embodying my invention, Fig. 2, an interior elevation of the same, and Fig. 3, a vertical section taken on line 3—3 of Fig. 1.

25 The preferred form of construction as illustrated in the drawing comprises a wall having tiles 4 embedded centrally therein between an inner wall 5 and an outer wall 6 of concrete. Wooden uprights 7 are also 30 embedded in the inner wall portion 5 with their inner faces flush with the inner face thereof and the laths 8 are secured to said uprights. In actual practice the uprights 7 and laths 8 secured thereto are preferably 35 formed in sections, the abutting sections of the uprights 7 being connected together at their meeting ends by means of dowels 9 and the concrete is filled into the wall construction after the lath sections are placed in 40 position. The uprights 7 are frusto-pyramidal in horizontal section with their larger portions placed inwardly so as to effect a dovetail connection between the lath construction and the concrete to prevent ready 45 withdrawal of the same.

Vertical iron rods 10 are embedded in the outer concrete wall portion 6 immediately adjacent the outer sides of the tiles 4 and are connected with dowels 9 by means of tie

wires 11, thus firmly tying the construction 50 together. An outer wall 12 having an inner sheet iron lining 13 provided with vertical and horizontal ribs 14 is provided to facilitate the forming of the concrete construction, the ribs 14 serving to imitate portions 55 of stone as will be readily understood.

To further add to the ornamental appearance of the wall, horizontal strips 15 are arranged across the inner face of the wall 12 to produce corresponding recesses in the 60 walls as will be readily understood. Uprights 16 are arranged against the outer face of wall 12 and are held in position by bolts 17 passing horizontally through the construction as indicated to hold the parts 65 in place during formation of the concrete construction, tubes 18 being embedded in the construction to accommodate bolts 17 and permit of their ready withdrawal after the construction has set.

70 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

75 Having described my invention what I claim as new and desire to secure by Letters Patent is:

1. A building construction comprising a wall of concrete formation having wooden 85 uprights embedded in the inner portion thereof, said uprights being formed in sections with dowels connecting said sections; upright metallic rods embedded in said concrete formation; and wire tie members connecting said dowels and rods, substantially 90 as described.

2. A building construction comprising a wall of concrete formation having wooden 95 uprights embedded in the inner portion thereof with their inner faces flush with the inner face of said formation, said uprights being formed in sections with dowels con-

necting said sections; upright metallic rods embedded in said concrete formation; wire tie members connecting said dowels and rods; and horizontal tubes embedded in 5 said wall formation, substantially as described.

In testimony whereof I have signed my

Copies of this patent may be obtained for five cents each, by addressing the "Commissioner of Patents, Washington, D. C."

name to this specification in the presence of two subscribing witnesses.

ACHILLES H. VAN PAEMEL.
